(57) **CLAIM**

The ornamental design for a tactile payment card, as shown and described.

DESCRIPTION

FIG. 1 is a perspective view of a tactile payment card showing my new design according to a first embodiment;

FIG. 2 is a front plan view thereof;

FIG. 3 is a rear plan view thereof;

FIG. 4 shows a top elevation view thereof;

FIG. 5 shows a bottom elevation view thereof;

FIG. 6 is a left elevation thereof;

FIG. 7 is a right elevation view thereof;

FIG. 8 is a perspective view of the second embodiment of the tactile payment card;

FIG. 9 is a front plan view thereof;

FIG. 10 is a rear plan view thereof;

FIG. 11 shows a top elevation view thereof;

FIG. 12 shows a bottom elevation view thereof;

FIG. 13 is a left elevation view thereof;

FIG. 14 is a right elevation view thereof;

FIG. 15 is a perspective view of the third embodiment of the tactile payment card;

FIG. 16 is a front plan view thereof;

FIG. 17 is a rear plan view thereof;

FIG. 18 shows a top elevation view thereof;

FIG. 19 shows a bottom elevation view thereof;

FIG. 20 is a left elevation view thereof; and,

FIG. 21 is a right elevation view thereof.

The broken lines shown in the drawings, including in FIGS. 1, 2, 8, 9, 15, and 16 are for illustrative purposes only and form no part of the claimed design.
